UNITED STATES PATENT OFFICE.

LEWIS H. JOHNSON, OF BLOOMFIELD, NEW JERSEY, ASSIGNOR TO WESTERN ELECTRIC COMPANY, INCORPORATED, OF NEW YORK, N. Y., A CORPORATION OF NEW YORK.

TELEPHONE-EXCHANGE SYSTEM.

1,210,653.

Specification of Letters Patent.

Patented Jan. 2, 1917.

Application filed May 26, 1916. Serial No. 99,975.

To all whom it may concern:

Be it known that I, LEWIS H. JOHNSON, a citizen of the United States, residing at Bloomfield, in the county of Essex and State of New Jersey, have invented certain new and useful Improvements in Telephone-Exchange Systems, of which the following is a full, clear, concise, and exact description.

This invention relates to telephone exchange systems, and more particularly to such systems of the central energy type in which an operator's telephone set is automatically connected to and disconnected from a calling telephone line.

The object of this invention is the provision of means for increasing the efficiency of the operators of a telephone exchange and for facilitating the completing of connections between subscribers.

In accordance with this invention, a telephone exchange system, in which the operator's telephone set is automatically connected to a calling telephone line upon the connection of a link circuit therewith, is provided with circuits and apparatus so organized that, while the operator's telephone set is connected to one calling telephone line, it cannot be connected to any other calling line, but a second connection may be prepared during the existence of the first so that upon the disconnection of the operator's telephone set from the first calling line, it will be immediately connected to the calling line forming a part of the prepared connection.

This invention is an improvement on that disclosed in the application of Henry P. Clausen, Ser. No. 59,972, filed November 6, 1915, in that less apparatus is required for accomplishing the desired result.

More specifically this invention contemplates a telephone exchange system in which there are link circuits for interconnecting subscribers' lines and a relay associated with each link circuit operating upon connection of the link circuit with a calling subscriber's line to include an operator's telephone set in circuit therewith, the operation of any one listening relay establishing a short circuit for all other listening relays of that position, whereby an operator is prevented from being connected to more than one line at the same time.

This invention is illustrated in the accompanying drawing, in which there are shown

ordinary subscribers' lines A, B, C, and D (lines B, C and D being indicated merely by the jacks thereof) and cord circuits E and F for interconnecting the subscribers' lines. The apparatus of each cord circuit is exactly alike, and the same reference characters will be used in each to indicate the same apparatus.

Assuming that subscriber A wishes to converse with subscriber B, A will signal the central office in the usual manner, whereupon the operator will insert the answering plug of the cord circuit E in the jack associated with A's line, causing the operation of sleeve relay 5 and supervisory relay 6. The operation of supervisory relay 6 causes the operation of listening relay 7 over a circuit from battery, through resistance 8, common conductor 9, contact 10 of relay 7, contact 11 of relay 12, winding of relay 7, alternate contact of relay 6 and supervisory lamp 13 to ground. Listening relay 7, in operating, connects an operator's telephone set 15 across the talking strands of cord circuit E, and completes a locking circuit for itself from battery, through contact 16 of relay 7, contact 11 of relay 12, winding of relay 7, alternate contact of relay 6 and supervisory lamp 13 to ground. Contact 16 of relay 7 makes before contact 10 breaks, so that the circuit of relay 7 remains closed. The operation of relay 7 also closes its contact 17, which puts a direct ground on the common conductor 9 and short-circuits the listening relays of all other cord circuits in that position. The operator, finding the desired number to be that of subscriber B, completes the connection by inserting the calling plug of the cord circuit E into the jack associated with B's line, causing the operation of relay 12, which opens the locking circuit of relay 7, permitting it to release and causes the lighting of supervisory lamp 20. The release of listening relay 7 of cord circuit E disconnects the operator's telephone set from this cord circuit and opens its contact 17, removing the short circuit of all other listening relays in that position. The operator actuates ringing key 21 to send ringing current over B's line to operate the call bell thereat. Sub- 100

scriber B, in responding, removes the receiver from the switchhook, causing the operation of supervisory relay 22 to efface supervisory lamp 20. When conversation is completed, both subscribers restore the re- 110

ceivers to the switchhooks, causing the lighting of supervisory lamps 13 and 20 to furnish disconnect signals, whereupon the operator removes both plugs from the jacks, restoring all apparatus to normal.

While the operator was busy completing connections between subscribers A and B, and before the calling plug of the cord circuit E was inserted into the jack of B's line, subscriber C may have called. The operator could take up this call by inserting the answering plug of cord circuit F into the jack of C's line. Relays 5 and 6 of cord circuit F would be operated, but the listening relay 7 thereof would not operate, because of the short circuit of this relay maintained by the actuated condition of listening relay 7 in cord circuit E. As soon, however, as the operator completes the establishment of connection between lines A and B, relay 7 of the cord circuit E will be released, as hereinbefore described, thereby removing the short circuit of the listening relay 7 of cord circuit F, which thereupon operates over a circuit similar to that described for relay 7 of cord circuit E. The operation of this relay of cord circuit F establishes a short circuit for the listening relays of all other cord circuits in that position, including the relay 7 of cord circuit E. The connections between lines C and D may be completed in the same manner as described in connection with the establishment of connections between lines A and B.

It will be noted from the drawing and 35 from the above description that this invention provides simplified means for increasing the efficiency of the operators of a telephone exchange and reduces the time required for completing connections between 40 subscribers' lines.

What is claimed is:

1. In a telephone exchange system, subscribers' lines terminating at a central office, link circuits for interconnecting said lines, an operator's telephone set, a relay associated with each link circuit operating upon connection thereof with a calling line to include the operator's telephone set in circuit therewith, and a short circuit for all other relays 50 established upon the energization of one of the relays, whereby the operator's telephone set can be connected to only one line at a time.
2. In a telephone exchange system, subscribers' lines terminating at a central office, link circuits for interconnecting said lines, an operator's telephone set, a relay associated with each link circuit operating upon connection thereof with a calling line to include the operator's telephone set in circuit therewith, and a normally open circuit multiplied to each of the relays completed by the operation of any one of the relays to establish a short circuit of all other relays. 55

In witness whereof, I hereunto subscribe my name this 24th day of May, A. D. 1916.

LEWIS H. JOHNSON.
